(57) **CLAIM**

I claim the ornamental design for a bicycle tire, as shown and described.

DESCRIPTION

FIG. 1 is a perspective view of a bicycle tire according to the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a partial perspective view of a section taken between line 8-8 of FIG. 1; and,

FIG. 9 is a cross-section view taken along line 9-9 of FIG. 2.

The broken lines in the drawings are for the purpose of illustrating portions of a bicycle tire that form no part of the claim.
